SPOON OR SIMILAR ARTICLE OF FLATWARE

Richard C. Gavette, Hampton, N.H., assignor to Fortunoff Silver Sales, Inc., Westbury, N.Y.

Filed Aug. 7, 1972, Ser. No. 278,406

Term of patent 14 years

Int. Cl. D7—03

U.S. Cl. D7—137

Fig. 1.

Fig. 2.

Fig. 3.

Fig. 4.

Fig. 5.

Fig. 6.

FIG. 1 is a front elevation view of a spoon or similar article of flatware showing my new design;

FIG. 2 is a side elevation view thereof;

FIG. 3 is a rear elevation view thereof;

FIG. 4 is a cross-sectional view on an enlarged scale taken along section 4—4 of FIG. 1 thereof;

FIG. 5 is a cross-sectional view on an enlarged scale taken along section 5—5 of FIG. 1 thereof; and

FIG. 6 is a cross-sectional view on an enlarged scale taken along section 6—6 of FIG. 1 thereof.

The design is intended for use on sets comprising spoons, forks, knives and similar articles of flatware.

I claim:

The ornamental design for a spoon or similar article of flatware, substantially as shown and described.
